UNITED STATES PATENT OFFICE.

GEORGE A. HENDERSON, OF CHARLESTON, WEST VIRGINIA.

AEROPLANE.

1,164,717.

Specification of Letters Patent. Patented Dec. 21, 1915.

Application filed February 26, 1910. Serial No. 546,292.

To all whom it may concern:

Be it known that I, GEORGE A. HENDERSON, a citizen of the United States, residing at Charleston, in the county of Kanawha and State of West Virginia, have invented a certain new and useful Improvement in Aeroplanes, of which the following is a full, clear, and exact description, reference being had to the accompanying drawings, forming part of this specification, in which—

Figure 1 is a perspective view of an aeroplane embodying my invention. Fig. 2 is a transverse vertical section, with certain parts omitted for clearness of illustration. Fig. 3 is a detail view showing a part of the propeller driving gearing. Fig. 4 is a perspective view showing one end of the aeroplane and the manner of mooring it. Fig. 5 is a perspective view showing a portion of one of the carrying planes. Figs. 6 and 7 are detail views hereinafter referred to.

My invention has relation to aeroplanes, and is designed to provide an aeroplane whose carrying planes and propellers are so located and arranged that the latter will force large volumes of air against the planes which are thereby caused to utilize air currents of the machine's own creation instead of the free air ahead of them.

A further object of my invention is to generate air currents within the machine of sufficient volume and velocity to overcome natural air currents and conditions which would otherwise affect the course and equilibrium of the machine.

The nature of my invention will be best understood by reference to the accompanying drawings showing one embodiment of my invention, which will now be described, it being premised, however, that the broader features of my invention are capable of various embodiments within the scope of the appended claims.

In these drawings, the letter F, wherever seen, designates the frame work of the machine, which may be in general of any suitable character. As shown, it consists of a plurality of circular members set vertically and spaced from each other, and connected by longitudinally extending tie-members B having the inwardly bent end portions C.

S designates a center shaft, supported suitable bearings (see Fig. 3) in the frame work F, and driven by motors M. These motors are supported within suitable cars K, which are located centrally within the cir-

cular members of the frame work, as shown in Fig. 2. The shaft S carries a number of bevel gear wheels X rigidly secured thereto, and which mesh with and drive corresponding wheels X' on radial shafts S'. The shafts S', at their outer ends carry bevel gear wheels X² which mesh with and drive bevel gear wheels X³ on the propeller shafts S². A number of these shafts S² (in the present instance six are shown) surround the shafts S, being spaced about equally from said shaft and from each other. (See Fig. 2.) Secured to each shaft S² are propellers P, set at intervals from each other. Surrounding each propeller, is a fixed circular guard G, adjacent guards being connected by connectors, preferably of stiff spring steel, as shown in Fig. 2. The guards G are also secured to the circular frame members and constitute a part of the framework. Each guard also has spoke members G' which support central bearing hubs G⁴ for the shafts S². These hubs are preferably provided with ball bearings.

J designates the supporting or carrying planes of the machine. Four of these are shown, but any desired number may be employed. One of these planes is located between each adjacent pair of circular frame members around the cars K. (See Fig. 5.) Each plane is rigidly secured to a transverse bar J^a which extends through and is mounted in bearings in the corresponding car. The bars J^a have cranked central portions, one of which is connected to a pivoted lever J' designed to be moved backward and forward by the operator within the forward car and to be set in a fixed position by means of a suitable pawl and rack bar device J². The series of bars J^a are connected together in any suitable manner so as to be moved in unison by the operator in the forward car and who can thus set the planes J at any desired angle for the purpose of effecting changes in the altitude of the machine in flight.

Y designates control members in the form of relatively small planes whose inclination can be changed to thereby affect the inclination of the machine as a whole. One of these members is placed in the rear of the three forward sets of propellers, but other members may be placed at various positions as required.

R is a rudder which is located at the extreme rear end of the machine, but within

the area of the air currents created by the machine. This rudder may be operated by any suitable connections (not shown).

When at rest, the machine is designed to be moored to a post, tree, or other suitable anchor T. For this purpose I provide the mooring cables T¹, connected to the framework of the machine and which converge at their opposite ends and are connected to a Y-shaped link or clevis T². The ends of this link or clevis carry bearings for two sliding rods T³, normally pressed toward each other with their inner ends in contact by means of springs t. The rods engage an eye t² which is connected to the anchor T by the connection T'. T⁴ is a release wire or cable which is connected to the rods T³ in a manner to effect their separation.

In starting, when the propellers have generated a sufficient force to lift the machine (without the machine's traveling upon the surface of the earth for any distance or acquiring forward momentum in its entirety with respect to the earth), the operator manipulates the release wire T⁴ to separate the sliding bars T³. This releases the machine from its anchorage, and the machine rises.

In alighting, the entire weight of the machine rests and is supported by an elastic cradle suspended from the main frame and embracing the lower portion of the machine. The cradle is free to oscillate on its connections C² with the main frame, and the weight of the runners B' and wheels B² carried by the cradle is sufficient to cause it to remain parallel with the earth notwithstanding the lateral tilting of the machine proper. The connections C² which suspend the cradle from the main frame are sufficiently flexible to permit of this relative movement between the main frame and the cradle. The wheels B² are for the purpose of enabling the machine as a whole to be moved from place to place along the ground.

The cars K are preferably located slightly below the machine's vertical center, their weight, together with that of the motors therein, tending to insure equilibrium.

The strength, per square foot, and the entire area, of the planes used, in this machine, must be, before their actual construction, and use, exactly determined by the following units: (1) The lifting capacity of a square foot of such plane, inclined at a given angle, when there is presented to its under-surface, an air current of a given velocity; (2) the fixing of that given velocity of air-current, by measuring its force at a given distance in the rear of propellers of consistent construction, revolved at a given number of revolutions per minute; and the location of such propellers on shafts approximately at distances forward of such planes, when such distances are so determined; such distances depending upon the

capacity of the machine designed to be built, and consequently its size and power; (3) the fixing of the weight of the entire machine, (with its motors, consistent with its lifting capacity, so determined), at a number of 70 pounds so substantially less than the maximum capacity as to permit of sufficient plane-surface being exposed to such self-generated currents, in flight, as will maintain equilibrium and altitude after, by 75 accident to the propellers, motors, or otherwise, a substantial percentage of the aggregate air current in the machine is withdrawn from the effective plane surface.

The application of sufficient power, by the 80 means herein described, will result in the uniform vertical revolution of so many of propellers PP as may be required to lift and move forward the machine in the air, by the onrush of the generated air currents upon 85 the planes, properly inclined.

It will be apparent from the foregoing that the distinctive feature of my invention is in the provision of means whereby the machine creates its own immediate air conditions, and whereby such conditions are sufficiently powerful to exclude or overcome natural currents of free air and other natural conditions which would otherwise unfavorably affect the course, speed, or 95 equilibrium of the machine. This created air condition is substantially continuous throughout the length of and around the machine, so that none of its parts are directly exposed to the free air through which 100 it passes, and is sufficient in cyclonic force per square foot to furnish the maximum resistance to the propellers and also to overcome outside air currents of ordinary velocity.

The vertical revolution of the forward propellers, at about the limit of their safe speed, results in their using all free air available in front of and partially to the sides of them, which they are capable of 110 using, for generating propelling force.

The faster the blades are propelled through the free air ahead, the more nearly is supplied the maximum resistance those propellers are capable of using in furtherance of their object. It will, therefore, be noted, at this point that no dead, air-resisting surface is presented to the free air on the machine's onward course—the area of surface so presented being active, controlling surfaces. This eliminates resistance to the forward movement of the machine, which would exist in the machine if inactive surfaces therein were pushed against the air in front of it; and, in addition, tends to 115 create a suction by slightly tending to create a vacuum in front of the moving machine, partially in so far as a vacuum may be tended to be created in the open air.

The location of propellers on sets of shafts 130

at proportionate distances in the rear of the forward propellers, and revolving them by motors therefor provided in cars K, results in there being presented to the forward surfaces of the second set of propellers, more air resistance, and consequently more propelling force, and the revolutions of the said second set of propellers tend to increase the volume of air controlled by the machine, or 5 affected by it, to the further exclusion of outside, normal or abnormal, atmospheric conditions. The affixing of the third set of propellers, substantially as shown, when revolved in conjunction with other propellers, 10 results in the securing of correspondingly more air-resistance for use in itself, both from the increased inrushing speed of that air forced back through the front and second propellers, and from lateral suction; 15 and the location of such other propellers, substantially as shown, will result in correspondingly increased propelling force of each of them over that force possible by their independent operation. The combined 20 action of all the propellers, surrounding the said cars K, will encircle the machine and all of its parts with such a force of its own as will completely overcome outside atmospheric interferences, and attain the maximum 25 air-resistance on its propellers' surfaces, within itself, for its use in propelling itself at such maximum speed, to the substantial exclusion of outside resistance to its forward movement, in furtherance of the 30 object of my invention.

The operation of the propellers in moving the machine forward, as aforesaid, will, depending upon the proper adjustment of the planes JJ, and the controls YY, maintain 35 the altitude of the machine when in flight, or according to the angle at which such planes and controls are adjusted, cause the machine to gradually rise, by reason of the onrushing of the air, (so generated within 40 the machine's radius, and there so uniformly controlled by it) to and against the properly inclined surfaces of said planes JJ and controls YY, with the result that when the machine is traveling at a high speed the 45 planes and controls may be, by the operator, gradually adjusted, proportionately as such speed increases, to a position approximately parallel with its shafts, frame work and cars, for, because of the increased pressure 50 on the undersides of said planes and controls, almost infinitesimal inclination of the same is required to maintain the machine in its normal traveling altitude; and the resistance of such planes and controls to the 55 air then forced against them, (though within the radius of the machine itself, and generated by it), in the beginning of its flight, is correspondingly eliminated, resulting in accelerated speed attained. At this point it 60 is well to particularly call attention to the 65

fact, as shown, that the planes and controls, as well as the machine's rudder, are all within the radius of the currents of air generated and controlled within the machine itself; and that no part of them extend beyond the forward or rear propellers, except the said rudder, which, located in the sectional center of the rear of the machine, is surrounded by the current of air in the machine's wake, and not affectable, therefore, by cross or other outside air-currents; and that at no time does any part of either the controls, planes or rudder, present their surfaces to aught but the uniform controlled and fixed current of air generated within the machine, already used by it in its propelling capacity, and extending uniformly throughout the length and breadth of the entire machine in such volume and velocity as to overcome, exclude and expel cross or other interfering air-currents, rather than to seek to adapt the aerial-planes to such cross-currents, after such planes have been attacked by them.

The machine's carrying capacity is limited only by its size and power. Its passengers are sufficiently housed within the cars K, to avoid inconvenience from the high pressure of wind generated about said cars K by the machine's mechanism.

Instead of planes of the form shown, I may use any other suitable form; the number of propellers may be varied; the operating connections can be widely changed; any suitable form of gearing may be employed for connecting the motors with the propeller shafts, and various other changes may be made within the scope of my claims.

I claim:—

1. An aeroplane, having a sustaining plane, and a set of propellers mounted to revolve on normally horizontal axes, said set being disposed around a central longitudinal axis of the aeroplane and all the propellers of the set acting to create an artificial atmosphere about the sustaining plane; substantially as described.

2. An aeroplane having a plurality of transverse sustaining planes arranged in tandem, and a set of propellers for creating an artificial atmosphere around each plane, the propellers of each set being mounted on normally horizontal axes, and the sets being in tandem about a common longitudinal axis of the aeroplane; substantially as described.

3. An aeroplane having a plurality of transverse sustaining planes arranged in tandem, and a set of propellers for creating an artificial atmosphere around each plane, the propellers of each set being mounted on normally horizontal axes, and the sets being in tandem about a common longitudinal axis of the aeroplane; the sets having a diameter greater than the transverse dimension of the planes; substantially as described.

4. An aeroplane having a plurality of transverse planes arranged in the central portion of the machine, a central motor-driven shaft, a plurality of propeller shafts arranged around the central shaft, and propellers carried by said shafts, together with means for varying the inclination of said planes; substantially as described.
5. An aeroplane comprising a series of circular frames, a plurality of transverse sustaining planes arranged in tandem between said frames and adjacent to the central portion thereof, and a plurality of propeller wheels carried by each of said frames and arranged to operate in circles of larger diameter than the transverse dimensions of the planes to create a dominating artificial atmosphere about the same, substantially as described.
6. An aeroplane having a relatively small normally horizontal supporting plane, and a series of propellers arranged in front of the plane and in a circle whose diameter is greater than the transverse dimension of the plane and thereby acting to entirely surround the plane with an artificial atmosphere sufficiently strong to overcome the effect of natural atmospheric currents in the air through which the aeroplane is passing, substantially as described.
7. An aeroplane having a relatively small supporting plane-surface, comprising a plurality of planes normally horizontal, and arranged in tandem, and a series of sets of propellers, the propellers of each set being mounted in a circle about a common longitudinal axis and to revolve in planes at substantially right angles to such axis and arranged to surround the planes with artificial air-currents, created by the propellers, and sufficiently strong to overcome the effect of natural air-currents in the free air through which the machine passes, substantially as described.
8. An aeroplane, having a plurality of sets of propellers arranged in tandem, the propellers of each set being arranged around a common longitudinal axis of the machine and mounted to rotate in planes at substantially right angles to such axis, and a plurality of relatively small planes arranged in tandem between the sets of propellers, said propellers creating the atmosphere which surrounds the planes and acting to exclude natural atmospheric air currents therefrom, together with a number of independent motors for driving the propellers, substantially as described.

GEO. A. HENDERSON.
